[57] CLAIM

The ornamental design for a collapsible radon monitor, as shown and described.

DESCRIPTION

FIG. 1 is a top and front perspective view of a collapsible radon monitor showing my new design, shown in an expanded position;

FIG. 2 is a top and front perspective view, shown in a collapsed position;

FIG. 3 is a front elevational view, shown in an expanded position;

FIG. 4 is a front elevational view, shown in a collapsed position;

FIG. 5 is a bottom plan view;

FIG. 6 is a top plan view; and

FIG. 7 is a left side elevational view thereof, the right side elevational view being identical.

The front and rear are identical in appearance and the left and right sides are identical in appearance for both the expanded and collapsed canister positions.
